SUET FEEDER FOR BIRDS

Michael R. Sheffler, Chalfont, Pa.

Application March 4, 1959, Serial No. 54,832

Term of patent 14 years

(Cl. D31—2)

Fig. 1 is a perspective view of a suet feeder for birds embodying my new design;

Fig. 2 is a top plan view thereof; and

Fig. 3 is a side elevational view thereof.

I claim:

The ornamental design for a suet feeder for birds, as shown.
